DESIGN FOR A HOSTESS TRAY

Milton L. Sturm, Chicago, Ill.

Application June 24, 1946, Serial No. 130,973

Term of patent 14 years

(Cl. D44—10)

To all whom it may concern:

Be it known that I, Milton L. Sturm, a citizen of the United States, residing at Chicago, in the county of Cook and State of Illinois, have invented a new, original, and ornamental Design for a Hostess Tray, of which the following is a specification, reference being had to the accompanying drawing forming a part thereof.

I claim:

The ornamental design for a hostess tray, substantially as shown.

MILTON L. STURM.
